APPARATUS FOR CONTINUOUSLY CASTING METALS

Frank F. Poland, Highland Park, N. J., assignor to
American Smelting and Refining Company,
New York, N. Y., a corporation of New Jersey

Application September 3, 1938, Serial No. 228,263

1 Claim. (Cl. 22—57.2)

The present invention is directed to apparatus for continuously casting metal in shapes of indefinite length.

It has long since been proposed to continuously supply metal to one end of a die or mold and continuously withdraw the cast metal from the other end thereof, the metal being solidified as it passes through the die or mold. However, experience has demonstrated that much of the apparatus suggested for the purpose is incapable of continuously producing sound castings and that other apparatus, while capable of producing sound castings, is commercially unattractive because of the slow casting speed inherent in its use. One of the main advantages of the present invention resides in its ability to continuously produce sound metal castings at relatively high casting rates or speeds.

Although the novel features which are believed to be characteristic of this invention will be particularly pointed out in the claim appended hereto, the invention itself, as to its objects and advantages, and the manner in which it may be carried out, may be better understood by referring to the following description taken in connection with the accompanying drawing forming a part thereof, in which

Fig. 1 is a sectional elevation of one form of apparatus incorporating the features of the invention,

Fig. 2 is a horizontal section taken on the line 2—2 of Fig. 1, and

Fig. 3 is a side elevation of a portion of the apparatus shown in Fig. 1.

Referring more particularly to the drawing, 10 represents a portion of a furnace or reservoir for the molten metal 12. Mounted in the molten metal receptacle is mold 14, same being countersunk in the bottom of the receptacle and secured in place by lock nut 16. A cooling jacket 18 snugly surrounds the mold 14. Positioned at the exit of the mold 14 is cooling jacket 20 comprising a plurality of sections, as shown, yieldably interconnected by bolts 22 and springs 24, each of said sections having a liner 26. Pipes 28, 30 and 30a are provided for supplying cooling fluid to the mold water jacket 18 and the multi-sectioned cooling jacket 20, respectively.

The mold 14 is preferably of dense graphite meeting the specifications outlined in the co-pending application of Frank F. Poland and Karl A. Lindner, Serial No. 29,064 filed June 29, 1935, for Casting metal which issued as Patent No. 2,136,394 on November 15, 1938. It is illustrated in Fig. 1 as having a slight taper, an expedient found useful in the casting of small diameter rods but which may well be dispensed with in casting shapes of larger cross section inasmuch as shrinkage of the metal in such cases

will provide the clearance desired to prevent excessive friction between the mold and the solidified metal. The mold cooling jacket 18 and the multi-sectioned cooling jacket 20 are appropriately made of aluminum or copper and the liner 26 of jacket 20 may be of ordinary dense graphite inasmuch as solidification of the metal has normally taken place before the casting contacts said liner. In the drawing the cooling jacket 10 20 is shown to be held in position by the hinged members 32 affixed to the mold cooling jacket 18 and the split jacket 20. However, other means may be employed for holding the jacket in place. Also, the cooling jacket 20 may comprise a plurality of shorter similar cooling jackets and, further, instead of two split sections, different numbers of sections may be employed.

In performing the casting operation, the molten metal 12 is caused to continuously flow 20 from the receptacle 10 into the mold 14 by the continuous withdrawal of the starting rod or casting 34 by drive rolls, not shown. Solidification of the metal is effected in the mold 14, as indicated in Fig. 1, by vigorous circulation of water or other cooling medium through the jacket 18. From the mold 14 the solidified metal enters the multi-sectioned cooling jacket 20 where further heat is extracted from the hot casting by circulation of cooling fluid introduced to the jacket by pipes 30 and 38. Inasmuch as the various sections of the cooling jacket 20 are interconnected with spring bolts, as shown in Fig. 2, snug contact of the liner 26 with the casting is at all times maintained thereby promoting efficient heat extraction by the water jacket.

This application is a continuation-in-part of the prior application of Frank F. Poland, Serial No. 39,362, filed September 6, 1935.

While certain novel features of the invention have been disclosed and are pointed out in the annexed claim, it will be understood that various omissions, substitutions and changes may be made by those skilled in the art without departing from the spirit of the invention.

What is claimed is:

Apparatus for continuously casting metal comprising a receptacle for molten metal, a mold mounted in said receptacle, a unitary cooling jacket surrounding said mold, and a multiple-sectioned cooling jacket having its sections yieldably interconnected and self-adjusting with respect to the shape of solidified metal passed therethrough, characterized in that the walls of each of said sections define a passageway for the circulation of cooling fluid through the section out of contact with the solidified metal passing through the jacket.

FRANK F. POLAND.
